UNITED STATES PATENT OFFICE.

HIRAM TUCKER, OF CAMBRIDGEPORT, MASSACHUSETTS.

SPRING BED-BOTTOM.

Specification forming part of Letters Patent No. 13,188, dated July 3, 1855; Reissued April 5, 1859,
No. 683.

To all whom it may concern:

Be it known that I, HIRAM TUCKER, of Cambridgeport, in the county of Middlesex and State of Massachusetts, have invented 5 an Improved Spring-Sacking for a Bed or Mattress; and I do hereby declare that the same is fully described and represented in the following specification and the accompanying drawings, letters, figures, and references thereof.

Of the said drawings Figure 1, denotes a top view of my invention; Fig. 2, is a transverse section of it taken through one of its sectional parts or bearers, the same exhibiting 15 it in its normal position; Fig. 3 is another transverse section exhibiting such sectional bearer as it appears when depressed by a weight laid upon it, the object of this latter section being to exhibit the 20 positions of the flexible band loops thereof under such circumstances.

In these drawings, A, represents a rectangular frame in which are to be arranged a series of sectional bearers, such as will be 25 hereinafter described. Each of these bearers is composed of an inflexible bar, B, (formed of wood or other suitable material) two lifter or stirrup springs C, C', and two longitudinal helical tension springs D, D'. 30 Every stirrup spring C, or C' operates to raise its bar, B, upward and it is made of a piece of wire bent somewhat in the form of the letter, U, and also in helices around a staple, E, inserted in and made to project 35 from the inner side of one of the longitudinal bars, a, of the frame, A, each end of the spring being fixed in the bar a.

The distance between the two lifter springs C, C', of each sectional bearer should be 40 somewhat greater than the length of the inflexible bar, B, to which they are connected by flexible band loops F, F', as seen in the drawings. Each of these band loops, consists of a piece of leather, linen, webbing, 45 or other material having the elasticity of the same. It is doubled made to extend around the upper or transverse part of the spring and to be fastened to the underside of the bar B; the length of that part of the 50 band which extends from the end of the bar to the spring being about equal to, or somewhat greater than thickness of the bar, B. This method of connecting each bar, B, with a stirrup spring causes the flexible 55 band loop to turn upward and toward the

end of the bar whenever a weight is placed on the bar so as to sink it out of its normal position or into that as represented in Fig. 3, and it is for the purpose of not only preventing undue and improper longitudinal strain upon the stirrup spring, but also for constituting a joint which is noiseless in its operations.

Each of the longitudinal tension springs, is fastened at one end, to a projection or ear, b, extending downward from the bar, B, the other end of the spring being hooked into a staple, c, which is inserted as seen in the drawings in one of the bars, a, of the frame, A.

The object of the springs, D, D, is not so much to elevate the bar B, as to contribute steadiness to its movements, and prevent it from such longitudinal swaying, as would tend to injure the lifter springs C, C'. A 70 mattress or bed foundation composed of a series of the bars, B, and their lifter and tension or counter swaying springs arranged to and within a frame as hereinbefore described, constitutes not only an agreeable 75 and durable support for a mattress or bed, but it is one in which there is little or no liability of its being sagged in the middle as ordinary spring beds are liable to be by constant use, such being prevented by the 80 peculiar construction or combination of each 85 sectional part or bearer. Each of said bearers being entirely independent of the rest, and not connected to such by any bands or strips extending longitudinally of the frame 90 A, is left perfectly free to accommodate 95 itself to any downward strain which may be brought to bear upon it. While the stirrup springs prevent it from tipping or turning over laterally and serve to raise it vertically 100 the tension springs beside operating as above set forth contribute also to its vertical elevation and to counteract the greater part of the strain which may be brought to bear upon it, the combined springs operating to 105 excellent advantage. I would also state that the inflexible bar operates to support only that part of the mattress imposed on it, while the lifter springs not only perform such operations (and in a manner different from what an ordinary spiral spring would) but another, viz., that of raising the bar and the parts directly over them. The lifter springs in some respects may be said to operate like inflexible bars, jointed to the 110

frame, A, and the inflexible bar, B, and sustained on springs.

I am aware that an inflexible bar, extended entirely across the frame and supported on spiral springs has been used in a bed foundation. I do not claim such, nor consider such as making part of my invention as it is liable to sag in the middle and is objectionable in other respects. My great 10 object has been to prevent such sagging by employing an inflexible bar extending only partially and transversely under the bed and jointed to other supports or springs extended across the remainder of the distance 15 between the sides of the frame. Such I have found by experience to produce an elastic sacking, which when combined with and supported by counter swaying springs as described, presents not only durable properties 20 and freedom from noise, but an ease to a person reposing on the mattress, such as is rarely if ever to be met with in a spring bed as ordinarily constructed.

I would remark that I do not claim an arrangement of helical springs and horizontal 25 and transverse bands, wherein, not only is

each of the longitudinal bands connected to its supporting frame by a helical spring extended from each end of such band to the adjacent end or bar of such frame, but each 30 transverse band or strip of spring steel is connected to the frame by four helical springs, two of which are fastened to each end of such strip, but

What I claim is as follows:

I claim the improvement of arranging and connecting the inflexible bar B, and lifter and counter sway springs (or their equivalents) together and within the frame, A, so that each when a mattress is laid upon 40 it shall extend under against and give support to such mattress and operate as an elastic foundation therefor substantially in the manner as stated.

In testimony whereof I have hereunto set 45 my signature this ninth day of March A. D. 1855.

HIRAM TUCKER
